UNITED STATES PATENT OFFICE

160,316

LOCOMOTIVE BODY

John F. Halbeisen, Detroit, Mich., assignor to
Chrysler Corporation, Highland Park, Mich., a
corporation of Delaware

Application July 20, 1949, Serial No. 4,028

Term of patent 14 years

(Cl. D66—1)

To all whom it may concern:

Be it known that I, John F. Halbeisen, a citizen of the United States, residing in the city of Detroit, county of Wayne, and State of Michigan, have invented a new, original, and ornamental Design for a Locomotive Body, of which the following is a specification, reference being had to the accompanying drawings, forming part thereof, in which:

Figure 1 is a perspective view taken from the front end of a locomotive body embodying my design;

Figure 2 is a side elevational view of the locomotive body shown on a somewhat smaller scale;

Figure 3 is a front elevational view of the locomotive body shown on a scale somewhat enlarged over that of Figures 1 and 2; and

Figure 4 is a perspective view looking down on the top and front of the locomotive body and on

a scale somewhat reduced from that of Figure 3.

The side opposite that shown in Figures 1 and 2 is substantially the same as that shown in Figures 1 and 2.

The dominant features of my design reside in the portions shown in full lines.

I claim:

The ornamental design for a locomotive body, substantially as shown and described.

JOHN F. HALBEISEN.
